UNITED STATES PATENT OFFICE.

CHARLES A. GREEN, OF CHICAGO, ILLINOIS, ASSIGNOR TO C. F. PEASE COMPANY, A CORPORATION OF ILLINOIS.

ARC LAMP.

Original application filed October 11, 1922, Serial No. 593,672. Divided and this application filed June 18, 1925. Serial No. 38,069.

This invention relates to improvements in arc lamps used in blueprint work, photoengraving, and other arts.

The object of the invention is to provide an improved arc lamp so constructed as to permit the use of higher voltages with increase of current and correspondingly longer and heavier arcs, the light from which contains a larger percentage of near violet and ultra-violet rays than is the case with arc lamps heretofore used for photographic work of this character.

Another object is to provide an arc lamp in which it is possible to use a smaller globe 15 with a higher energy input than in other arc lamps of the same electrical capacity, or of the same size.

Additional objects will be apparent from the description hereinafter given of one embodiment of the invention as used in connection with a continuous blueprint machine, although the invention is not limited to this embodiment thereof, or to said class of service.

25 This application is a division of my pending application, Serial No. 593,672, filed October 11, 1922.

In the drawings:

Fig. 1 is an elevation, partly in section, 30 of a part of a blueprint machine.

Fig. 2 is a top plan view of the row of arc lamps used therein, and

Fig. 3 is an elevation of said arc lamps.

The blueprint machine comprises a suitable frame 1 having a table 2, over which the operator slides the blueprint paper on which the tracings are superimposed. The tracings and the blueprint paper travel rearwardly under a guide 3 and upwardly along an endless belt 4, which slides over a curved glass support 5, and is supported and moved by a series of rollers 6, 7 and 8, the roller 6 constituting the driving roller.

45 The printing is done as the prints travel slowly past the curved sheet of glass, the tracings and blueprints issuing at the top of the machine and being fed forwardly onto a sheet metal supporting plate 9, over which they slide into a sheet metal receptacle 10.

50 The arc lamps are supported on a transverse pipe or conduit 11, carried by the frame of the machine, each lamp having a supporting frame 12 of non-magnetic material, preferably, aluminum. The lower 65 end of this frame surrounds the conduit

11, providing a hinged support which permits the lamp to be swung forwardly for inspection or trimming. The aluminum frame carries a supporting plate 13 of magnetic material, such as cast-iron, on which the various parts of the arc lamp are mounted. The mechanism for feeding the carbon downwardly is mounted on this support and includes a solenoid 14 and suitable clutch mechanism of well known construction forming no part of the present invention.

A glass globe 15 is mounted on an extension 16 constituting part of the arc lamp aluminum frame. A reflector 17 is arranged 70 in front of the globe to distribute the light evenly to the rear over the blueprint paper.

In the arc lamps used heretofore, the arc which formed between the upper and lower electrodes or carbons had a tendency to blow 75 to one side, as an iron frame was employed as a support for the structure. It was, therefore, necessary to mount the solenoid or magnet in each lamp fairly high above the points of the carbons, resulting in a 80 long lamp. In the present construction the frame is made of aluminum, which has a number of very desirable properties, including its non-magnetic property, and said frame is mounted below the solenoid, the 85 latter being mounted not far above the arc, and the lamp being correspondingly shorter. In this construction, and with the arrangement of the arc lamps in a row, as shown in Figs. 2 and 3, the bowing of the 90 arc to one side has been greatly minimized.

Referring to Fig. 3, the arc which forms between the carbons 18 and 19 in each case has a tendency to blow to the right, this tendency being offset, however, by the magnetic field established by the solenoid of the adjacent lamp. The right hand lamp having no lamp to the right of it to compensate in the manner described, I provide a strip of magnetic material 20, preferably 100 a piece of mild steel, which is secured to the right hand lamp of the group, as shown in Figs 2 and 3. Said strip brings the magnetic field in such proximity to the arc as to counteract its tendency to blow to the 105 right. As a result of this arrangement the arc is comparatively steady and centrally located with reference to the carbons.

In the prior constructions, previously referred to, the arc in blowing out to one 110

side would consume one side of the carbon, the upper end of the arc terminating at a point considerably above the lowest point of the carbon, the lower end being un-
 5 symmetrical in shape. This projecting lower point caused a shadow to be thrown which interfered with uniform printing. With the present arrangement the upper carbons are symmetrical in shape at their lower ex-
 10 tremities and the arc travels slowly around said lower ends, consuming them evenly and furnishing a light which is free from shadows. As shown in Figs. 2 and 3, the supply wires 21 enter the conduit 11 with
 15 branch connections issuing from the outlet boxes 22. Figs. 2 and 3 also show a slightly diagonal arrangement of each lamp with reference to the axis of the supporting conduit. This arrangement results in some im-
 20 provement in the magnetic field.

In the absence of the improvements de-
 scribed, bowing of the arcs occurs and dis-
 turbs the uniformity of the lighting effect.

At the upper end of each globe, and with-
 25 in the same, is a casing 23 having suitable holes 24 in it to permit the escape of heated gases. By virtue of the smaller construc-
 tion of the frame and associated parts, pre-
 30 viously referred to, I am enabled to use a smaller globe, which, in turn, results in drawing in the outside air more advanta-
 geously, the air being drawn in at the top of the globe and expelled intermittently
 35 through the same openings, as the success-
 40 sive installments of air heat up and expel themselves. Under these conditions less oxygen is drawn in at a time, and there is less irregularity in the heating. This permits the use of said smaller globes without
 45 danger of cracking them.

The construction described also permits the use of higher voltages with increase of current and correspondingly longer and heavier arcs. The longer arcs emit a greater proportion of rays effective for blueprinting and photography generally than the shorter arcs, and increase the printing speed. With my improved construction I am en-
 50 abled to increase the current used twenty-five percent with an increase in printing speed of about one hundred percent, with improved results from the standpoint of uniformity in the prints.

The improvements described herein are applicable both to alternating current and direct current lamps, although the improvement over the prior practice is more pronounced in the case of lamps used on alternating current circuits. Heretofore it has been necessary to design arc lamps especially for alternating current or direct current use as applied to photographic work, whereas with my improved construction the same lamp may be used in either work, making it a universal arc lamp.

What I claim is:

1. An arc lamp comprising a magnetic supporting plate, a solenoid mounted above the same, an aluminum frame depending from said plate, upper and lower electrodes supported from said plate and said aluminum frame, respectively, and a globe enclosing said electrodes whereby the structure below said plate may be short without causing irregular consumption of said electrodes by the arc.

2. An arc lamp comprising a supporting member, a solenoid mounted above the same, a non-magnetic frame depending from said member, upper and lower electrodes on said member and said non-magnetic frame respectively, and a globe enclosing said electrodes whereby the structure below said member may be short without causing irregular consumption of said electrodes by the arc.

3. An electric arc lamp comprising a non-magnetic frame, actuating mechanism for the carbons mounted above said frame, whereby the arc maintains an average central position with reference to the axis of said carbons, a small globe supported by said frame and surrounding the electrodes enabling a high voltage to be employed with large current consumption, resulting in a long arc within said globe and the development of light wave lengths suitable for photographic work.

4. An arc lamp comprising a supporting member, a solenoid arranged on one side of said member, a non-magnetic frame supported by said member, upper and lower electrodes, and a globe enclosing the same.

In testimony whereof, I have subscribed my name.

CHARLES A. GREEN.
